UNITED STATES PATENT OFFICE.

MARCUS L. WRIGHT, OF NEWTON, ASSIGNOR OF ONE-HALF TO LYSANDER WRIGHT, JR., OF NEWARK, NEW JERSEY.

LAST-BLOCK FASTENER.

SPECIFICATION forming part of Letters Patent No. 417,350, dated December 17, 1889.

Application filed June 25, 1889. Serial No. 315,484. (No model.)

To all whom it may concern:

Be it known that I, MARCUS L. WRIGHT, a citizen of the United States, residing at Newton, Sussex County, New Jersey, have invented certain new and useful Improvements in Last-Block Fasteners, fully described and represented in the following specification and the accompanying drawings forming a part of the same.

10 The object of this invention is to furnish an economical and effective means of securing the last-block upon the last; and the invention consists, primarily, in the combination, with a vertical central slot formed in 15 the upper end of the last-block, of a spring-wire inserted through such slot into the last, a catch upon the upper end of the spring, and a pin secured transversely to the slot (upon the outer side of the block) to engage with 20 such catch.

It also consists in the combination, with such fastening devices, of a spring applied to the last within a recess in the block to lift the block from the last when uncaught.

25 In the annexed drawings, Figure 1 is a longitudinal section of the last adjacent to the fastening devices. Fig. 2 is a side view of the body of the last. Fig. 3 is a plan of the same. Fig. 4 is a plan of the last-block, and 30 Fig. 5 a view of the staple supporting the locking-pin.

a is the body of the last; b, the instep or last-block; c, a spring-wire having one end inserted in the last a and extended along the 35 upper surface of the last.

d is a recess formed in the under side of the last-block to admit the spring.

f is a central vertical slot formed in the upper end of the block b, and f' the spring 40 catch-wire inserted in the last and projected upward through the slot.

e is a wire pin applied transversely to the end of the slot, as shown in Fig. 4, and preferably made in staple form, as shown in Fig. 5, 45 with its ends inserted in the block b at each side of the slot.

The lower end of the last-block is preferably formed with a point b², as shown in Fig. 4, to fit a corresponding recess b' in the last, 50 as in Fig. 3, and the outer end of the spring f' is bent into a catch or round eye g, the

under side of which engages with the upper surface of the pin e, and operates by its pressure upon the pin to hold the point b² in the recess b' and to clamp the upper end of the last-block firmly down upon the last. When the last-block is thus locked in its working position, the spring c is compressed and operates, when the catch formed by the eye g and pin e is released, to lift the last-block up with 60 the pin above the eye g. The eye formed in the end of the spring f' operates not only as a catch by the contact of its under side with the pin e, but as a handle to bend the spring, which may be readily effected by the fingers 65 or by inserting a suitable tool in the eye to retract it.

I am aware that swinging catches have been pivoted upon the last to hold the upper end of the last-block, as in United States 70 Patents Nos. 341,478, issued May 11, 1886, and 145,082, issued November 25, 1873, and that a catch formed of a spring secured to the last and having its free end adapted to engage with the last-block has also been used, as in 75 United States Patents Nos. 268,271, issued November 28, 1882, and 208,513, issued October 1, 1878; and I do not, therefore, claim a 80 spring-catch broadly, nor any construction except that shown and described herein.

I also disclaim the above-mentioned patents. The slot f is intended to fit closely the sides of the spring-pin f', and the pin thus serves, in addition to its function as a catch, to hold the last-block firmly from lateral movement 85 upon the body a. The eye g is a convenient form for the catch upon the spring f' to engage the cross-pin e; but the precise form of the catch is immaterial. It is evident that the pin e might be formed perfectly straight 90 and inserted in the body of the last-block, across the slot f, without departing from my invention, as it would perform the same function in such case that it does when formed as a staple with its ends driven into the block 95 on each side of the slot. I do not, therefore, limit myself to the construction for the pin shown herein.

What I claim, and desire to secure by Letters Patent, is—

1. The combination, with the last a, having 100 the spring f', and catch g, of the last-block b,

provided with the central slot *f*, and the transverse pin *e*, the whole arranged and operated as and for the purpose set forth.

2. The combination, with the last *a*, having 5 the spring *f'*, formed with eye *g*, and the spring *c*, arranged as described, of the last-block *b*, formed with the central slot *f*, and having the pin *e*, formed with the feet *e'* inserted in the block at opposite sides of the slot, and provided with the recess *d* to receive the spring,

the whole arranged and operated substantially as set forth.

In testimony whereof I have hereunto set my hand in the presence of two subscribing witnesses.

MARCUS L. WRIGHT.
